UNITED STATES PATENT OFFICE

GEORGE D. HARRINGTON, OF SEAGIRT, NEW JERSEY; NORMA HARRINGTON AND LAWRENCE T. HARRINGTON HEIRS AT LAW OF SAID GEORGE D. HARRINGTON, DECEASED

PULVERIZER

Application filed November 17, 1926. Serial No. 148,815.

This invention relates to pulverizers.

Pulverizers of various types have been used for many years for breaking up hard materials such as ore, cement, limestone, clinkers, chemicals and so forth. Such pulverizers, however, have been heavy and cumbersome in construction and expensive to manufacture.

At the present time when the price of coal of the larger grades is prohibitive, the use of pulverized or powdered coal is coming to the fore as a satisfactory solution and as a method of overcoming the high cost of producing heat for residences and manufacturing plants. By utilizing pulverizers to reduce the coal to the desired fineness, very low grades of coal can be used such as rice, buckwheat, mine run and washer waste.

This invention relates particularly to centrifugal pulverizers and the invention has for its salient object to provide a device of this type so constructed that it can be operated at very high speeds, thus causing the material acted upon to be thrown out at a very high velocity and be thus broken up.

Another object of the invention is to provide a pulverizer that can be economically manufactured and can be used in factories or houses to break up cheap grades of coal.

Another object of the invention is to provide a device so constructed that the parts thereof will be durable and will not be easily worn away by contact with the material operated upon.

Another object of the invention is to provide in a pulverizer, means for controlling the size or grade of the product discharged from the machine.

Further objects of the invention will appear from the following specification taken in connection with the drawings, which form a part of this application, and in which

Fig. 1 is an elevational view of a device constructed in accordance with the invention and illustrated in connection with a furnace;

Fig. 2 is an elevational view taken at right angles to Fig. 1, this view being partly broken away;

Fig. 3 is an enlarged sectional elevation

showing the details of construction of the pulverizer;

Figs. 4 and 5 are sectional elevations taken substantially on lines 4-4 and 5-5 of Fig. 3;

55

Fig. 6 is an enlarged sectional elevation taken substantially on line 6-6 of Fig. 5.

The invention briefly described consists of a pulverizer comprising a disk upon which the material to be broken up is fed, the disk 60 having vanes thereon adapted when the disk is rotated to throw the material at a high velocity against a serrated or corrugated ring which surrounds the outer periphery of the disk. A fan casing is mounted adjacent the 65 disk and in the form of the invention illustrated, above the disk and has an inlet opening disposed above the central portion of the disk through which the powdered material is sucked by the fan which operates in the fan 70 casing. This powdered material is discharged from the fan casing at the periphery thereof and as shown in Figs. 1 and 2, the discharge pipe or conduit from the fan casing can be used to feed the material directly 75 to a furnace. The upper surface of the disk and the outer surfaces of the vanes are covered with relatively soft, non-metallic material, such as rubber, and this is also true of the arms and blades of the fan. This 80 form of construction materially increases the length of life of the parts covered and also causes the device to operate more quietly. Means is provided for regulating the suction of the fan and this is accomplished by adjustable air inlets in the fan casing and between the fan casing and the disk, by regulating the size of the opening into the fan casing from the pulverizing chamber, by an adjustable opening for the hopper chamber 90 and by an adjustable gate valve in the discharge conduit from the fan chamber. By properly regulating all of these openings, the suction can be so controlled as to determine the grade of the pulverized material 95 sacked into the fan casing from the pulverizing chamber.

Various novel features are incorporated in the pulverizing apparatus, suction chamber and fan and in the air control devices 100

and these will be brought out in more detail in the following specification.

In the particular embodiment of the invention illustrated, the apparatus is mounted on a base 10 upon which is also mounted a motor M for driving the operative parts of the device. A frame 11 is supported on the base and this frame in turn supports a frame 12 on which is mounted a hopper 13 which receives the material to be pulverized and from which the material is fed downwardly through a chute 14. A feed roller 15 is positioned at the lower end of the chute and a gate valve 16 controls the amount of material fed into a chamber 17 by the roller 15. The roller may be driven in any suitable manner from the motor M. A hinged cover 18 is positioned at the top of the chamber 17 and can be adjusted to control the admission of air into this chamber.

The material from the feed chamber 17 is discharged into a pulverizing chamber 20 formed by a rotatable disk 21, carried by a shaft 22, and by a stationary ring 25 which surrounds the periphery of the disk and extends upwardly therefrom.

The pulverizing chamber is covered at the top by a plate 30 which is secured as shown in Fig. 4 to side frame members of the supporting frame 11. The ring 25 is secured to the plate in the manner shown in Fig. 6, namely by hook bolts 31 provided with hooks 32 at their lower ends which engage in a groove 33 formed in the lower surface of the ring 25. The plate 30 is provided with an opening 35 registering with the delivery end of the feed chamber 17 and is also provided with a central opening 36 disposed as shown in Fig. 3 over the central portion of the disk 21. The plate 30 has secured thereto above the opening 36, an adjustable iris diaphragm 37.

This diaphragm is operated in the usual well known manner by an arm or lever 38 and the central opening 39 in the diaphragm can be regulated as to size by moving the arm or lever 38. The disk 21 has formed on or secured to its upper surface a plurality of radial vanes 40 which extend substantially to the outer periphery of the disk. The vanes 40 are substantially triangular in shape at their outer ends as shown at 41 and are also triangular in end elevation and in top plan. In other words, each of the vanes at its outer end 41 has a rearwardly extending projection which tapers downwardly and rearwardly. The outer ends 41 of the vanes are so formed for the purpose of preventing air pockets in the rear of the vanes which act as a drag and tend to maintain a partial vacuum. When such pockets are formed, the pulverized material tends to collect therein.

The upper surface of the disk as shown at 45 is covered with a non-metallic, relatively soft material, such as rubber and the vanes

are also covered with rubber or if desired, may be formed of rubber. This covering on the disk and vanes prolongs the life of the elements covered by protecting them from abrasion and also provides a quietly operating structure. The upper surface of the disk 21 at the outer periphery thereof is slightly elevated or thickened as shown at 46 for the purpose of giving a slight upward movement of the material being operated on as it is thrown out by the vanes and leaves the disk.

The front faces 47 of the vanes are substantially radial and the outer ends 48 are inclined slightly with respect thereto. The ring 25 is provided with a series of internal serrations or notches 49 having front surfaces 50 (with respect to the direction of travel of the disk) disposed substantially radially of the disk.

Thus, when the vanes and the disk rotate, the material carried thereby will be thrown substantially perpendicularly by the vanes against the surfaces 50 and since the disk rotates at a very high rate of speed, such, for instance, as 5,000 R. P. M., the material will be thrown against the surfaces or facets 50 of the ring at a very high velocity.

The under surface of the plate 30 as shown at 51 is also covered or lined with a non-metallic, relatively soft material, such as rubber. A fan casing or housing 55 is secured to the top of the plate 30 preferably by welding the casing to the plate. The bottom 56 of the fan casing is spaced from the plate 30 by a downwardly extending annular flange 57 at the outer edge thereof. The flange 57 does not extend entirely around the outer edge of the bottom 56 of the fan casing but there is an opening 59 formed therein, the web forming the flange 57 extending inwardly as shown at 60 and 61 to form walls for the opening. The opening 59 forms an air intake for the fan and the size of this opening is controlled by adjustable wings 62 and 63 connected by links 64 to a screw 65 which extends through a lug 66 and is adjustable by means of nuts 67 and 68. By moving the wings 62 and 63 inwardly or outwardly, the air intake to the fan can be regulated.

The top of the fan casing is closed by a cover 70 which is secured to the plate 30 by studs 71 fixed to the plate 30 and extending through the cover plate 70. Nuts 72 are threaded on the upper ends of the studs and secure the plate 70 in tight engagement with the wall of the casing 55.

The shaft 22 is mounted at its upper and lower ends respectively in ball bearings 75 and 76 carried by bearing brackets 77 and 78 fixed to the frame 11. The shaft is enlarged at its upper end as shown at 80, thus providing a shoulder 81. The fan consists of a disk 85 which is secured between washers 86 and 87 and is provided at its outer end with fan

blades 88. The washers 86 and 87 are mounted on the shaft 22. The upper washer 86 abuts against the shoulder 81 and the lower washer 87 is held in position by a sleeve 90 which surrounds the shaft 22.

5 The disk 21 is also secured to the shaft by a pair of washers 91 and 92. The washer 91 above the disk abuts against the lower end of the sleeve 90 and the washer 92 is threaded on a threaded portion 93 of the shaft 22 and is held in position by a lock nut 94. It will be evident that as the washer 92 and the lock nut 94 are turned, the impeller or pulverizing disk and the fan will be securely 10 clamped in position on the shaft 22. Attention is called to the fact that the threads on the portion 93 of the shaft are left hand threads so that the rotation of the disk and shaft will not loosen the connection between 15 the disk and the shaft.

20 The under surface of the cover 70 of the fan casing, the upper surface of the bottom 56 of the fan casing, the upper and lower surfaces of the fan disk 85, the inner surface of 25 the casing wall and the outer surface of the fan blades 88 are all covered with some suitable non-metallic, relatively soft material, such as rubber as shown at 95 to prevent abrasion and render these parts more durable and less subject to wear.

20 The fan casing 55 has a discharge conduit 98 secured thereto to which is connected a conduit 99 for conducting the pulverized material to a storage bin or if desired, as 35 shown in Fig. 1, to a furnace 100. A slide valve 101 between the conduits 98 and 99 controls the discharge of the material from the fan casing.

35 The cover plate 70 of the fan casing is provided with an opening 105 controlled by a pivoted gate valve 106 mounted above the cover plate 70 and controlled by a handle 107.

40 The shaft 22 may be driven in any suitable manner and as shown in the drawings has 45 a pulley 115 mounted thereon connected by a belt 116 to the motor M. Suitable covers 117 and packing washers 118 may be provided for the bearings 75 and 76 to prevent dust or extraneous material from entering 50 the bearings.

Operation

55 The material to be pulverized is placed in the hopper 13 and is fed from the chute 14 by the feed roller 15, the amount of material fed being controlled by the slide valve 16. This material thus passes into the feed chamber 17 and from this chamber is fed by gravity onto the impeller or pulverizing disk 21. 60 The disk is rotated at an exceedingly high rate of speed and the material as it strikes the disk, is immediately thrown outwardly at a high velocity by the vanes 41 and as it strikes the facets 50 on the ring 25 which is 65 preferably formed of manganese steel or very

hard material, the material being acted upon is broken up. If it is not sufficiently pulverized, it will bound back into the path of a succeeding vane and will be again thrown against the facets and again broken up. The 70 suction of the fan in the fan casing above the pulverizing disk will cause the finely divided material to pass upwardly through the opening in the diaphragm 37 when the material is sufficiently divided to be fed upwardly by 75 the suction. The amount of suction, and, therefore, the grade of the material fed can be controlled by several different control devices, namely, by the damper or gate valve 18, by the adjustable wings 62 and 63 which 80 control the air intake 59, by the adjustable iris diaphragm 37, by the adjustable gate valve 106 and by the slide valve 101 which controls the discharge from the fan.

85 By properly setting these various control valves, the amount of material fed through the fan housing and the fineness or grade of the material can be regulated.

90 By reason of the coverings on the pulverizing elements and fan elements and also on the fan casing, abrasion of these parts is prevented and they are rendered much more durable and quieter in operation.

95 From the foregoing description, it will be seen that the device described comprises few 95 parts, is simple and durable in construction and, furthermore, the device will effectively perform the desired objects.

100 Although one specific embodiment of the invention has been particularly shown and described, it will be understood that the invention is capable of modification and that changes in the construction and in the arrangement of the various cooperating parts may be made without departing from the 105 spirit or scope of the invention, as expressed in the following claims.

105 What I claim is:

110 1. A pulverizer comprising a substantially horizontal disk, means for rotating the disk, vanes secured to and extending upwardly from the upper surface of the disk, an internally corrugated stationary ring extending around the outer periphery of the disk, a fan casing disposed above the disk and having 115 an opening registering with the central portion of the disk, a fan in said casing, said fan casing having a discharge opening at the outer periphery thereof, and means for feeding material to the outer peripheral portion 120 of said disk.

125 2. A pulverizer comprising a substantially horizontal rotatable disk, radially disposed vanes carried thereby and extending upwardly therefrom, and a ring surrounding said disk and extending above the disk, said vanes having extensions in the rear thereof for preventing air pockets.

130 3. A pulverizer comprising a substantially horizontal rotatable disk, radially disposed

vanes carried thereby and extending upwardly therefrom, and a ring surrounding said disk and extending above the disk, said vanes having rearwardly and downwardly tapered extensions for preventing air pockets in the rear of the vanes.

4. A pulverizer comprising a substantially horizontal disk, a ring surrounding said disk, vanes on the disk for throwing material 10 against said ring, a plate above said disk and having an opening therethrough, a fan casing above said plate and spaced therefrom, and a chamber between the fan casing and plate, said chamber having an air intake opening 15 therein and said casing having an opening communicating with the chamber.

5. A pulverizer comprising a substantially horizontal disk, a ring surrounding said disk, vanes on the disk for throwing material 20 against said ring, a plate above said disk and having an adjustable opening therethrough, a fan casing above said plate and spaced therefrom, and a chamber between the fan casing and plate, said chamber having an air intake opening 25 therein and said casing having an opening communicating with the chamber.

6. A pulverizer comprising a substantially horizontal disk, a ring surrounding said disk, 30 vanes on the disk for throwing material against said ring, a plate above said disk and having an opening therethrough, a fan casing above said plate and spaced therefrom, and a chamber between the fan casing and 35 plate, said chamber having an adjustable air intake opening therein and said casing having an opening communicating with the chamber.

7. A pulverizer comprising a substantially horizontal disk, a ring surrounding said disk, vanes on the disk for throwing material 40 against said ring, a plate above said disk and having an adjustable opening therethrough, a fan casing above said plate and spaced therefrom, and a chamber between the fan casing and plate, said chamber having an adjustable air intake opening therein and said casing having an opening communicating with the chamber.

50 8. A pulverizer comprising pulverizing mechanism, a plate covering said mechanism and having an opening therethrough, a fan casing above said plate and spaced therefrom, and a chamber between the fan casing and plate, said chamber having an air intake opening 55 therein and said casing having an opening communicating with the chamber.

9. A pulverizer comprising a substantially horizontal disk, a ring surrounding said disk, 60 vanes on the disk for throwing material against said ring, a plate above said disk and having a central opening therethrough, a fan casing above said plate and spaced therefrom, and a chamber between the fan casing and plate, said chamber having an air intake open-

ing therein and said casing having an opening communicating with the chamber.

10. A pulverizer comprising a substantially horizontal disk, a ring surrounding said disk, vanes on the disk for throwing material 70 against said ring, a plate above said disk and having an opening therethrough, a fan casing above said plate and spaced therefrom, and a chamber between the fan casing and plate, said chamber having an air intake opening 75 therein and said casing having a central opening communicating with the chamber.

11. A pulverizer comprising a substantially horizontal disk, a ring surrounding said disk, vanes on the disk for throwing material 80 against said ring, a plate above said disk and having a central, adjustable opening therethrough, a fan casing above said plate and spaced therefrom, and a chamber between the fan casing and plate, said chamber having an air intake opening 85 therein and said casing having an opening communicating with the chamber.

12. A pulverizer comprising a substantially horizontal disk, vanes carried thereby, a ring surrounding said disk, a cover plate for 90 said disk having a central opening therein, and a fan having an intake opening disposed above and in communication with the opening in said plate.

13. A pulverizer comprising a substantially horizontal disk, vanes carried thereby, a ring surrounding said disk, a cover plate for 95 said disk having a central, adjustable opening therein, and a fan having an intake opening disposed above and in communication with the opening in said plate.

14. A pulverizer comprising a substantially horizontal disk, vanes carried thereby, a ring surrounding said disk, means for feeding material to said disk adjacent the outer periphery thereof, a cover plate for said disk having a central opening therein, and a fan having an intake opening disposed above and in communication with the opening in said plate.

15. A pulverizer comprising a shaft, a substantially horizontally disposed pulverizer impeller mounted on said shaft, a ring surrounding said impeller and a cover plate over 115 said ring, and a fan casing above said impeller and communicating with the pulverizing chamber formed by said impeller, ring and plate.

16. A pulverizer comprising a shaft, a substantially horizontally disposed pulverizer impeller mounted on said shaft, a ring surrounding said impeller and a cover plate over 120 said ring, a fan casing communicating with the pulverizing chamber formed by said impeller, ring and plate, and a fan in said casing and mounted on said shaft, said impeller, cover, fan casing and fan being covered with non-metallic, relatively soft material.

17. A pulverizer comprising a shaft, a sub-

stantially horizontally disposed pulverizer
impeller mounted on said shaft, a ring sur-
rounding said impeller and a cover plate over
said ring, a fan casing communicating with
the pulverizing chamber formed by said im-
peller, ring and plate, a fan in said casing and
mounted on said shaft and a plurality of
means for controlling the suction of the fan.

18. A pulverizer comprising a feed cham-
ber, means for feeding material into said
chamber, said chamber having an opening in
the upper end thereof, means for regulating
the size of said opening, pulverizing mecha-
nism communicating with said chamber and
15 receiving material therefrom, and suction
means above said pulverizing mechanism for
withdrawing the finely divided pulverized
material therefrom.

In witness whereof, I have hereunto set my
20 hand this 8th day of November, 1926.
